Charles Luxton

United States Patent Office.

CHARLES LUXTON, OF HUDSON, NEW JERSEY.

Letters Patent No. 64,681, dated May 14, 1867.

IMPROVED PEAT MACHINE.

The Schedule referred to in these Letters Patent and making part of the same

---

TO ALL WHOM IT MAY CONCERN:

Be it known that I, CHARLES LUXTON, of the city of Hudson, in the county of Hudson, and State of New Jersey, have invented a Machine for Compressing "Peat" for fuel or manufacturing "bricks." I do hereby declare that the following is a full and exact description, to wit:

The nature of my invention is such that the "turf" or "clay," after being properly prepared, is passed into the "feeding-box," (marked as such on the drawing,) from thence passed on to the "octagon roller," the revolving motion of the said octagon roller supplying the "lever" for compression. The said roller removes the same, and is taken from the machine by the "apron" marked apron on drawing.

What I claim as my invention, and desire to secure by Letters Patent, is—
The "octagon roller," in combination with the "lever," for compressing "peat" fuel or for making "bricks."

CHARLES LUXTON.
